UNITED STATES PATENT OFFICE.

GEORGE W. MATTERN, OF DAYTON, OHIO, ASSIGNOR TO THE CRAWFORD, McGREGOR AND CANBY COMPANY, OF DAYTON, OHIO, A CORPORATION OF OHIO.

DESIGN FOR A STRIKING-FACE FOR A GOLF-CLUB HEAD.

55,867.

Specification for Design.

Patented July 20, 1920.

Application filed August 12, 1919. Serial No. 317,063. Term of patent 14 years.

To all whom it may concern:

Be it known that I, GEORGE W. MATTERN, a citizen of the United States, residing at Dayton, in the county of Montgomery and State of Ohio, have invented a new, original, and ornamental Design for Striking-Faces for Golf-Club Heads, of which the following is a specification, reference being had to the accompanying drawing, forming part thereof.

The figure of the drawing is a perspective view of the club head showing my new design for a striking face therefor.

For illustrative purposes, the design has been shown applied to a driver. It is to be

understood, however, that this design of striking face is applicable to clubs of other shapes, as for instance brassies, putters, and those having heads of other shapes. No claim is therefore, made to the shape of the golf club head *per se*.

I claim:

The ornamental design for a striking face for a golf club head as shown.

In testimony whereof, I have hereunto set my hand this 6 day of August A. D. 1919.

GEORGE W. MATTERN.

Witnesses:

F. L. WALKER,
G. C. HELMIG.
